THUMB-DIALING HIGH VOLTAGE TELEVISION TEST PROBE

Joseph Woroble, 33 Morgan Place,
North Arlington, N.J. 07032

Filed June 29, 1966, Ser. No. 2,858

Term of patent 14 years

(Cl. D26—1)

FIGURE 1 is a side elevational view of the thumb-dialing high voltage television test probe of the present invention;

FIGURE 2 is a side elevational view of the portion of the other side of the probe which differs from the side shown in FIGURE 1;

FIGURE 3 is a top view thereof;

FIGURE 4 is a bottom view thereof;

FIGURE 5 is a front elevational view thereof, and
FIGURE 6 is a rear elevational view thereof.

I claim:

The ornamental design for a thumb-dialing high voltage television test probe, as shown.
